UNITED STATES PATENT OFFICE.

LOUIS MEYER, OF NEW YORK, N. Y.

PRINTING-PRESS.

1,231,282.

Specification of Letters Patent. Patented June 26, 1917.

Application filed January 4, 1917. Serial No. 140,528.

To all whom it may concern:

Be it known that I, LOUIS MEYER, a citizen of the United States, and a resident of the city of New York, borough of Bronx, 5 in the county of Bronx and State of New York, have invented a new and Improved Printing-Press, of which the following is a full, clear, and exact description.

My invention relates to printing presses 10 particularly adaptable for printing on continuous ribbons or tapes.

An object of the invention is to provide a simple, inexpensive and efficient printing press whereby sections of ribbon or tape of 15 different lengths can be printed on the press.

Another object of the invention is to provide a press whereby two colors may be printed.

With the above and other objects in view, 20 the nature of which will more fully appear as the description proceeds, the invention consists in the novel construction, combination and arrangement of parts as herein fully described, illustrated and claimed.

25 In the accompanying drawings, forming part of the application, similar characters of reference indicate corresponding parts in all the views.

Figure 1 is a longitudinal section through 30 a press embodying my invention on line 1—1, Fig. 2;

Fig. 2 is a top plan view;

Fig. 3 is a longitudinal section showing 35 diagrammatically the relative position of the various parts during the first operation, that is, during the impression with the first color;

Fig. 4 is a similar view showing the relative positions of the parts when the second 40 color is printed;

Fig. 5 is a similar view showing the position of the parts when the tape is fed through a predetermined length;

Fig. 6 is an enlarged sectional view 45 through the tension means on the printing roller;

Fig. 7 is a perspective view of the guide carrying the tension device;

Fig. 8 is a perspective view of the grip 50 control;

Fig. 9 is a perspective view of a corner of the type-carrying plate; and

Fig. 10 is a cross section through the bed 55 and type-carrying plate.

Referring to the drawings, 11 is the press frame in which a supporting drum 12 is

mounted to revolve. A bed 13 supported by rollers 14 also bears on the drum 12. A type-carrying plate 15 is mounted to slide longitudinally on the forward end of the 60 bed 13. The type-carrying plate has suitable means thereon for securing two independent chases 16 suitably spaced from one another. The motion of the plate on the bed is adjustable by means of set screws 17 65 provided on brackets 18 secured to the bed. The screws are disposed to engage a boss or projection 19 on the bed 13. When the set screws near the forward end of the plate are brought against the bosses 19, the forward chase 16 will be in position to properly print on tapes 20 which are carried by the pressure roll 21 mounted to revolve in the frame 11 above the bed 13. When the plate 15 is moved rearward, to bring the set screw 70 17 near the front of the plate in engagement with the boss 19, the front chase will be in position to properly print on the tapes 20.

The rolls of tape to be printed are carried 75 in a trough or receptacle 22 supported by the frame 11, suitable partitions 23 being provided therein for properly spacing the tape rolls. The pressure roll 21 carries a transverse guide 24 in which tension devices 80 85 25 are mounted to slide longitudinally of the guide, to properly engage the tape on the roller. Each tension device comprises a yielding member 26, one end of which is secured to a sliding block 27 engaging the 90 guide 24, and the other end of which is adapted to bear on the tape passing thereunder and supported by the printing roller. A set screw 28 is provided in the guiding block for varying the pressure of the yielding member upon the tape.

The tape 20, from the pressure roller, passes over a supporting bar 29 of the gripping mechanism, which is located on the extension of the frame in the rear of the press. 100 From the support the tapes pass to rollers 30 which have a frictional engagement with the shaft 31 to which rotary motion is imparted continuously by some suitable means not shown. The friction between the shaft 105 31 and the rollers 30 is such that they are only able to take up slack caused in the tape between the printing roller and said rollers 30.

The supporting bar 29 of the gripping 110 mechanism 32 is carried by a frame 33 which is adjustable on the rear extensions of the

frame 11 through the medium of set screws 34 mounted to engage bosses 35 on the extensions of frame 11. A shaft 36 is rotatably mounted in the frame 33 of the gripping mechanism 32. A pair of sharp-toothed combs 37 are secured to the shaft 36 so that the sharp teeth of the combs may come into engagement with the bar 29 when the shaft 36 is revolved. The movement of the combs 37 toward the bar is resisted by springs 38 which tend to maintain the combs away from the bar.

An arm 39 is secured to each end of the shaft 36 to revolve therewith. At its free end each arm carries a roller 40 which is to be engaged by a corresponding cam 41 secured to a plate 42 disposed transversely of the bed. Said plate 42 is secured to a flexible sheet 43 the rear edge of which is anchored to the rear edge of the bed 13. The front edge of the sheet 43 is bent upwardly to lie against the biased front edge of the plate 42 and to facilitate the engagement of said edge with wedge-shaped tongues 44 provided on the rear edge of the type-carrying plate 15. The tape 20 which lies above the plate 42 is protected therefrom by a guard 45 extending from the rear edge of the bed 13 over said plate, as best shown in Figs. 1 to 5 inclusive.

Each of the cams 41 has a slot 46 engaged by a screw 47 which anchors the cam to the plate 42. This arrangement permits an adjustment of the cam 41 relative to the roller 40 of the arm 39. The roller 40 has also an adjustment relative to the cam 41 by means of the set screws 34, but this adjustment is very limited. The cam 41 has a rearward extension 48 on which slides a cam portion 49 which is normally maintained against the main body of the cam 41 by a spring 50. The slide 49 of the cam has an arm 51 the length of which may be varied. The free end of each arm of the cams is adapted to be engaged by a corresponding arm 52 mounted to swing on the frame 11 (see Fig. 1).

The said arms are engageable by cams 53 provided on the end walls of the pressure roller 21. The end walls of the roller have arcuated slots 54 wherein the cams are adjustable so as to operate the levers 52 at predetermined angular displacements of said pressure roller. The pressure roller 21 has a tooth 55 for engaging a projection 56 on the bed to move the bed when the roller is rotated in the direction of the arrow, shown in Fig. 1, against the resistance of a weight 57 secured to the rear end of the bed. The tooth and projection serve for bringing the chases in proper register with the pressure roller. The weight 57 serves to restore the bed 13 to its initial position when the roller leaves the chases.

When two colors are to be printed on the

ribbon, the type-carrying plate 15 is moved inwardly until the front set screws 17 strike the boss 19. This will bring the front chase 16 into position (see Fig. 3). The movement of the bed inwardly will bring the wedge-shaped tongues 44 of the plate into engagement with the plate 42, raising the same, and in consequence bringing the lowermost points of the cams 41 above the rollers 40 of the arms 39. The pressure roller 21 is then rotated, displacing the bed in the direction indicated by the arrow in Fig. 3. The bed 13 and the plate 15 will therefore move, and the tapes carried by the roller will come into engagement with the rear chase 16.

As the pressure roller is returned the bed moves therewith, but the rollers 40 will not be engaged by the cams 41; therefore the gripping mechanism will not be operated, and as the printing roller is returned the tape that has been wound on the rollers 30 will unwind therefrom, for the tension device will prevent any slipping of the tape. As the roller leaves the chase the tooth 55 will be in engagement with the projection 56. Under the influence of the weight 57 the bed will be returned to its initial position. As the plate 15 is drawn on the bed to bring the rear set screws 17 against the projections 19, the plate 42 will be released and drop under gravity on to the bed 13, thereby bringing the cams 41 into the path of the rollers 40 when the bed is moved by revolving the pressure roller 21 (see Fig. 4).

In the return movement of the bed the rollers 40 will ride on their corresponding cams 41, bringing the sharp teeth of the combs on to the tapes thereunder. The teeth begin to engage the ribbon at the moment when the pressure roller leaves its contact with the chase, that is, on the latter part of the return movement of the pressure roller. In view of the fact that the springs 50 maintain the sliding part 49 of the cam against the main body of the cam, the roller 40 will pass on to the sliding part 49.

To release the teeth of the combs from the tapes the sliding parts 49 of the cam must be moved beyond the roller 40 to permit the same to drop so as to allow the spring 38 to raise the combs from the bar. To this end the pressure roller must be rotated in the direction shown in Fig. 5 until the cams 53 engage the swinging arms 52 and swing the same until the sliding parts 49 are moved to allow the rollers resting thereon to drop, as indicated in Fig. 5. By adjusting the cams 53 the engagement of the same with the swinging arms will take place sooner or latter. In consequence more or less tape will be pulled from the supply rollers resting in the trough 22. It is self-evident that the greater the angular displacement of the pressure roller after the combs have been made to engage with the tapes, the greater

will be the section of tape pulled from the supply rolls.

5 The adjustment of the cams on the plate 42 allows the proper adjustment between the gripping means at the time the roller leaves the chase.

10 As soon as the teeth have disengaged the ribbon, the slack that would have been produced by the revolving of the printing roller to bring the tooth 55 into engagement with the projection 56 of the bed is taken up by the tape rollers 30.

I claim:

15 1. In a printing press of the class described, a revoluble pressure roller, a type carrier mounted to slide, a tension device for retaining the tape on the roller, a gripping device for engaging the tape, means for actuating the gripping device operable 20 by the pressure roller, and means carried by the type carrier for rendering the operative device inoperative during the operation of the roller whereby a portion of the tape may be printed without causing a displacement 25 of the tape after it has been printed, substantially as and for the purpose set forth.

2. In a printing press of the class described, a revoluble pressure roller, a type carrier mounted to slide, a tension device for retaining tape on the roller, a gripping device for engaging the tape, means for operating the gripping device when the pressure roller leaves the type carrier, means 35 for preventing the operation of the gripping device operable by a sliding movement of the type carrier, and means for releasing the gripping means from the tape operable from the pressure roller.

40 3. In a printing press of the class described, a revoluble pressure roller, a type carrier mounted to slide, a tension device for retaining tape on the roller, a gripping device for engaging the tape, means for actuating the gripping device adapted to be operated by the pressure roller, and means for rendering said gripping operating means inoperative actuated by the type carrier.

45 50 4. In a printing press, a bed, a type carrier slidably mounted on the bed, a pressure roller mounted to engage the bed to bring the type carrier into engagement with the roller, a tension device for retaining tape on the roller, a gripping device for engaging the tape, means for actuating the gripping device mounted on the bed, means for operating the gripping operating means on the return movement of the roller, and means 55 associated with the type carrier for rendering the means for operating the gripping means inoperative.

60 65 5. In a printing press, a bed, a type carrier mounted to slide on the bed, a pressure roller adapted to displace the bed to bring

the type carrier into engagement with the pressure roller, means limiting the sliding movement of the type carrier on the bed whereby a predetermined part of the bed is brought into operative relation with the 70 pressure roller, tension means for retaining tape on the roller, a gripping device for engaging the tape, means for operating the gripping device mounted to participate in the displacement of the bed so as to operate 75 the gripping means on the return movement of the bed, means associated with the type carrier for displacing said means for operating the gripping device so as to prevent the engagement of said operating means 80 with the gripping device on the return movement of the bed, and means operable by the roller for controlling the means for operating the gripping device.

6. In a printing press of the class described, a bed, a type carrier slidably mounted on the bed, a pressure roller mounted to inwardly displace the bed for bringing the type carrier into engagement with the pressure roller, means limiting the sliding movement of the type carrier on the bed for maintaining the type carrier in predetermined relation with the pressure roller, tension means for retaining tape on the pressure roller, a gripping device for engaging 95 the tape mounted to be adjusted relative to the bed, means carried by the bed for actuating the gripping means on the outward movement of the bed, means controlling the gripping device, actuating means operable 100 by the return movement of the pressure roller after the same has disengaged the type carrier, and means associated with the type carrier for rendering the means for actuating the gripping device inoperative 105 during the outward movement of the bed.

7. In a printing press of the class described, a bed, a type carrier slidably mounted on the bed, a pressure roller mounted to displace the bed inwardly for 110 bringing the type carrier into engagement with the pressure roller, means limiting the sliding movement of the type carrier on the bed, tension means for retaining tape on the pressure roller, a gripping device for the 115 tape, means for operating the gripping device carried by the bed, means associated with the type carrier for rendering said means for operating the gripping device inoperative, and means operable by the pressure roller controlling the means for operating the gripping device.

8. In a printing press of the class described, a bed, a type carrier mounted on the bed, a pressure roller mounted to displace the bed inwardly for bringing the type carrier into engagement with the pressure roller, tension means for retaining the tape on the pressure roller, a gripping device for the tape, means for operating the 125 130 135

gripping device carried by the bed, a cam adjustable on the pressure roller, and means interposed between said cam and the means for operating the gripping device.

5 9. In a printing press of the class described, a bed, a type carrier on the bed, a pressure roller mounted to displace the bed inwardly for bringing the type carrier into engagement with the pressure roller, tension
10 means for retaining tape on the pressure roller, a gripping device for the tape, a cam on the bed for engaging the gripping device when the roller disengages the type carrier, a cam on the pressure roller, and motion
15 transmission means from the cam on the roller to the cam on the bed.

10. In a printing press of the class described, a bed, a type carrier, a pressure roller mounted to displace the bed inwardly
20 for bringing the type carrier into engagement with the pressure roller, tension means for retaining tape on the pressure roller, a gripping device for engaging the tape, a spring normally maintaining the gripping
25 device in inoperative position, a cam carried by the bed for bringing the gripping device into operative position, a sliding cam portion associated with the cam, a yielding member normally resisting the sliding movement
30 of the cam portion, a cam on the pressure roller, and motion transmission means from the cam on the roller to the sliding cam portion of the cam for the gripping device.

35 11. In a printing press of the class described, a bed, a type carrier, a pressure roller mounted to displace the bed inwardly for bringing the type carrier into engagement with the pressure roller, tension means
40 for maintaining the tape on the pressure roller, a gripping device for engaging the tape; a cam carried by the bed for bringing the gripping device into operative position, a sliding cam portion associated with the
45 cam, means normally resisting the sliding movement of the cam portion, a cam adjustable on the pressure roller whereby said cam may be brought into action by a greater or lesser angular displacement of the pressure roller, and motion transmission means interposed between the cam on the roller and the sliding cam portion.

55 12. In a printing press of the class described, a bed, a type carrier mounted to slide on the bed, means limiting the sliding movement of the type carrier on the bed, a pressure roller mounted to displace the bed for bringing the type carrier into engagement with the pressure roller, tension means for retaining tape on the pressure roller, a gripping device for engaging the tape, a cam carried by the bed for bringing the gripping device into operative position, means carried by the type carrier to operate the cam to place the same into inoperative position

relative to the gripping device, a sliding cam portion associated with the cam, means normally resisting the sliding movement of the cam portion, a cam on the pressure roller, and motion transmission means from the cam on the roller to the sliding cam portion to displace the same, whereby the gripping device is restored to its inoperative position.

70 13. In a printing press of the class described, a bed, a type carrier slidably mounted on the bed, a pressure roller mounted to displace the bed inwardly for bringing the type carrier into engagement with the pressure roller, tension means for securing a tape on the pressure roller, a gripping device for engaging the tape, a cam for actuating the gripping device secured to the bed to move under gravity toward the bed, means associated with the type carrier for displacing the cam from the bed whereby the cam is displaced from its operative relation with the gripping device, a cam section slidably relative to said cam, a yielding member normally resisting the sliding movement of said cam section, a cam on the pressure roller, and a swinging arm interposed between said cam on the roller and the sliding cam section for displacing said cam section after a predetermined angular displacement of the cam whereby said gripping device may be restored to its initial position.

75 14. In a printing press of the class described, a bed, a type carrier slidably mounted on the bed, a pressure roller mounted to displace the bed inwardly for bringing the type carrier into engagement with the pressure roller, tension means for retaining a tape on the pressure roller, a gripping device for engaging the tape, a cam for operating the gripping device, yielding means securing the cam to the bed whereby said cam is adapted to move to and from the bed, means carried by the type carrier for engaging said cam to move the same from the bed after a predetermined displacement of said type carrier on the bed, whereby said cam is placed inoperatively in relation to the gripping device, a cam section associated with the cam normally preventing the disengagement of said gripping device from said cam, a cam adjustably mounted on the pressure roller, and motion transmission means from the cam on the pressure roller to the cam section to displace the same, whereby the gripping device may be restored to its original position.

80 15. In a printing press of the class described, a bed, a type carrier, a pressure roller mounted to displace the bed inwardly for bringing the type carrier into engagement with the pressure roller, tension means for maintaining a tape on the pressure roller, a gripping device for engaging the tape, a cam adjustably mounted on the bed for

bringing the gripping device into operative position, a cam portion slidable relative to the cam for normally preventing the disengagement of the gripping device from the cam, and means for displacing said sliding cam portion operable from the pressure roller.

16. In a printing press of the class described, a type carrier mounted to slide on the bed, means limiting the sliding movement thereof, a pressure mounted to displace the bed inwardly for bringing the type carrier into engagement with the pressure roller, tension means for maintaining a tape on the pressure roller, a gripping device for engaging the tape, a cam support, a flexible member to secure said cam support to the bed whereby said support may be displaced from the bed, means associated with the type carrier for displacing the cam support from the bed by a predetermined displacement of said carrier on the bed, a cam mounted on said support to be adjusted longitudinally of the bed, said cam adapted to engage said gripping device when said cam support is resting on the bed, a cam extension slidable relative to the cam, means normally preventing the sliding movement of said cam extension whereby the gripping device is retained in the inoperative position, a cam on the pressure roller, motion transmission means from the cam on the roller to the cam extension for displacing the same to restore the gripping device to its initial po-

sition, and means whereby the cam on the pressure roller may be adjusted to allow a greater or lesser angular displacement of the pressure roller before the cam extension is actuated.

17. In a printing press of the class described, a bed, a type carrier, a pressure roller mounted to displace the bed for bringing the type carrier into engagement with the pressure roller, tension means for retaining a tape on the pressure roller, a gripping device for engaging the tape, a yielding member for restoring the gripping device to its initial position, a cam on the bed mounted to be adjusted longitudinally thereof, said cam being adapted to engage the gripping device on the outward movement of the bed when the roller leaves the type carrier, a cam extension slidable relative to the cam, means normally resisting the sliding movement of the cam extension from the cam, said cam extension being adapted to engage the gripping device and prevent the yielding member from restoring the gripping device to its initial position after the gripping device has been disengaged by the cam, and means for sliding the cam extension operable after a predetermined angular displacement of the pressure roller whereby the length of tape drawn by the roller may be varied substantially as and for the purpose set forth.

LOUIS MEYER.
